United States Patent Office.

GEORGE CROMPTON, OF WORCESTER, MASSACHUSETTS.

Letters Patent No. 94,401, dated August 31, 1869.

IMPROVEMENT IN LOOM.

The Schedule referred to in these Letters Patent and making part of the same.

To all whom it may concern:

Be it known that I, GEORGE CROMPTON, of Worcester, in the county of Worcester, and State of Massachusetts, have invented Improvements in Looms; and I do hereby declare that the following, taken in connection with the drawings which accompany and form part of this specification, is a description of my invention sufficient to enable those skilled in the art to practise it.

My invention relates partly to the combination and arrangement of the harness-mechanism of fancy-looms, and partly to an improved shipper-mechanism.

The drawings represent a loom-frame in which are mounted the parts of the mechanism directly connected with my improvements.

A shows an end elevation of the loom.

B, a rear view of the harness-mechanism.

C, an elevation of the shipper-mechanism, seen from the inside of the breast-beam.

D is a plan of the shipper-mechanism.

a denotes the frame.

b, the main shaft, carrying fast and loose pulleys, c d, banded to the driving-shaft e by a belt, f.

g denotes the harness frames, each sliding vertically between suitable guides, and each corded at top to the inner end of a horizontal lever, h, and at bottom to the end of a horizontal lever, i, the outer end of each upper lever, and outer end of each corresponding lower lever, being connected together by a vertical or upright jack, k, and an inclined cording, l, the jack being jointed at its upper end directly to the upper lever, and being connected with the lower lever by the inclined cording.

Outside of the jacks is the pattern-chain or cylinder m, against the contour of which the jacks are held by the stress of the inclined cording.

Each jack has upon its outer edge a hook, n, and upon its inner edge a hook, o, the outer hooks, when the jacks are pressed outward by the pattern-mechanism, being carried into engagement with a horizontal lifter-bar, p, and the inner hooks of jacks not so pressed outward, being held in position to engage with a depresser-bar, q.

For redistribution of the jacks after the shed has been formed by the rise and fall of the respective jacks, the hooks are brought into line by two long or overhanging evener-bars or levers, r. These levers are fulcrumed in or near the cloth-making plane, a fulcrum-plate, s, being bracketed to the frame a, said plate and each lever having for each fulcrum-pin u, an oblong slot, t, so that the fulcrum-point may be adjusted as circumstances may require.

The two evener-levers extend (respectively) over and under the upper harness-levers, and are actuated from the shaft b by cranks j and links v, (the latter

jointed to the vibrating ends of the evener-levers,) as will be readily understood.

The opposite ends of each lifter and depresser-bar move in guide-slots w, and near such ends, or on the opposite sides of the jacks, each lifter and depresser is connected to the evener-lever, in the same plane with it, by a pair of vertical connecting-rods x x or y y. Each lifter or depresser-bar has guides or projections z extending from it, which keep it from endwise movement, by sliding against the plates in which are the guide-slots w.

It will be obvious that as the evener-levers separate (or move away from the harness-levers after having evened the jack-hooks for distribution by the pattern-mechanism) each evener will impart a coincident and corresponding movement to the lifter or depresser with which it is connected, (thereby effecting the motion of the jacks and harness-frame connected thereto,) the evener and depresser not moving as levers, but as parallel bars, thereby dispensing with fulcruming both the eveners and the lifter and depresser-bars, and at the same time producing the requisite inclination in the shed.

Instead of fulcruming the eveners, the lifter and depresser-bars may extend out and be fulcrumed in the cloth-making plane, the eveners being then similarly connected, by pairs of parallel links x y, to the lifter and depresser-levers, without being fulcrumed.

It is in this organization of the lifter and depresser-mechanism, in connection with the other parts of the harness-mechanism, that this part of my invention consists.

The shipper-mechanism is as follows:

a' denotes the shipper-lever, carrying at one end the shipper-fork b', and connected at the other end to an upright latch-bar, c', (pivoted near the bottom of the frame,) the upper end of the bar passing through a slot, d', and resting, when the loom is operating, in a notch, e', while, when the loom is to be thrown off, the bar is carried to the end of the slot d'. Over the breast-beam, and extending the length thereof, is a long slide-rod or bar, f', sliding in bearings g', and connected, at its end adjacent to the arm c', to the end of one arm, h', of a bent lever, pivoted at i'.

On the inner side of the lever-arm h' is an incline, k', and the top of the latch-bar, when it rests in the notch e', is in the path of movement of this incline when the arm h' is moving toward the frame a. The outer arm, l', of the bent lever, is connected by a link, m', with a hook, n', jointed to an arm, o', on one end of a rocker-shaft, p', (mounted in bearings on the end of the frame a,) the opposite end of the shaft carrying an arm, q', from the end of which a pin projects into the groove of a cam, r', fixed to the loose pulley. The hook n' hooks at proper times over a pin, v', pro-

jecting from the latch-bar. When the latch-bar is thrown out from the notch, it is carried to the end of the slot d^2 , by the stress of a spring, s^2 , upon an arm, t^2 , of the latch-bar or lever, as will be readily understood, the latch-bar, in this position, keeping the shipper-fork in line with the loose pulley.

The normal position of the shipper-mechanism is shown in the drawings at C and D, the latch-arm being caught in its notch, and the shipper-lever holding the belt upon the fast pulley. When the attendant, standing at the opposite end of the loom, or at any point along the breast-beam, wishes to knock off the shipper-lever, to stop the loom, she moves the slide-bar f^2 from the shipper-mechanism, and in so doing brings the incline k^2 against the latch-arm, and throws such arm from its notch. The stress of the spring s^2 throws the latch-arm down to the end of the notch, causing the arm to move the shipper-lever and effect the transfer of the belt to the loose pulley. The transfer of the belt to the loose pulley sets the cam r^2 in rotation, causing the shaft p^2 to rock, and the hook n^2 to reciprocate. The movement of the slide, however, carries the hook n^2 above the pin v^2 on the latch-arm, so that the hook cannot catch upon it. When the loom is to be thrown on again, the attendant slides back the slide-bar f^2 , the movement thereby imparted to the bent lever carrying the hook down, so that as it moves outward it will drop over the pin, and as it moves inward will catch upon such pin and drag back the latch-arm, causing it (through movement imparted to it through the shipper-lever) to shift the belt back again upon the fast pulley, the latch-arm

catching in the notch e^2 , and thus holding the belt upon the fast pulley until the attendant wishes the loom to be again stopped.

The position of the mechanism, when the shipper-lever is knocked off, is shown in detail at E.

It is the combination of the long slide-bar and the incline for thus knocking off the shipper-lever, and the arrangement of the mechanism for effecting the knocking on of the lever, that constitute the latter part of my invention.

I claim—

1. In combination with the harness-frames, horizontal harness-levers, hooked jacks, inclined cording and pattern-mechanism, arranged substantially as described, the angular lifter, depresser, and eveners, when each evener (actuated by a connecting-rod from the crank-shaft, and pivoted at or near the cloth-making line,) is connected to and actuates its lifter or depresser, (which are not so pivoted,) having guides thereon, by means of parallel links or pairs of links, (or when the lifter and depresser are so pivoted and are connected to sliding unpivoted eveners,) substantially as described.
2. Also, in combination with the shipper-lever, the long slide-bar f^2 and incline k^2 , for knocking off the shipper-lever, substantially as described.
3. Also, the combination of the slide-bar f^2 , bent lever h^2 , hook n^2 , and latch-bar c^2 , for throwing on the shipper-lever, substantially as described.

GEO. CROMPTON.
